2,351,848

BREAKER TIMING

Edward A. Vogel, Beloit, Wis., assignor to Fairbanks, Morse & Co., Chicago, Ill., a corporation of Illinois

Original application May 7, 1941, Serial No. 392,312. Divided and this application November 9, 1942, Serial No. 465,011

1 Claim. (Cl. 200—80)

This invention relates to improvements in ignition devices for internal combustion engines, and has particular reference to an improved breaker timing mechanism of an automatic character. It is to be noted that the present application is a division of my application for improvements in Ignition device, filed May 7, 1941 and bearing Serial No. 392,312, Patent No. 2,346,094, April 4, 1944.

The principal object of the present invention is to provide an improved automatic breaker timing mechanism of centrifugally operated type, effective to regulate the breaker cam in its operative relation to the breaker points, responsively to changes in engine speed.

Other objects and advantages of the invention will become readily apparent from the following description of a preferred embodiment thereof, as exemplified by the accompanying drawing, in which:

Fig. 1 illustrates an ignition device which is shown partly in longitudinal section to disclose the improved breaker timing mechanism;

Fig. 2 is a fragmentary sectional elevation vertically through the device, as viewed from line 2—2 in Fig. 1, clearly illustrating features of the timing mechanism, and

Fig. 3 is a further fragmentary vertical section as taken from line 3—3 in Fig. 1, showing the breaker assembly.

Referring to the drawing by appropriate characters of reference, the ignition device apart from the present improved timing mechanism incorporated therein, may be of any suitable construction and as here shown, is of the battery ignition type. The device includes a casing portion 10 preferably of metal, as an aluminum alloy casting, and a casing portion 11 which may be of suitable non-magnetic material, as Bakelite. The casing portions in assembly, enclose in the upper section thereof, an induction coil unit 12, while the extension 14 of casing portion 11 serves to enclose a suitable distributor assembly (not shown). Casing 10 may be provided with a flange 15 through which the device may be mounted on the frame of the engine (not shown). The flange further may include a circular projection or rib 16 serving to properly locate and center the device in assembly to the engine for driven connection to a rotating part of the engine (not shown).

The end wall 19 of casing 10 is provided with aligned, external and internal bosses 20 and 22 respectively, through which extends a shaft-receiving bore 23, the bore being concentric with 55

the circular rib 16 as shown. Projecting through the bore and rotatably journalled therein by suitable sleeve bearing elements 24, is a shaft 26, the outer end of which carries a coupling device 27 for driven connection of the shaft to the engine crankshaft or other operating part of the engine (not shown). It is to be noted that the bosses 20 and 22 on casing wall 19, provide the sole bearing support for the shaft 26. The inner end portion 28 of the shaft 26 projects beyond the adjacent boss 22, and is axially recessed, as at 30, to receive and freely journal therein a spindle or stub shaft 31. The stub shaft 31 has its outer end portion enlarged and formed to provide a cam 32, of the form shown in end elevation in Fig. 3, for operating the circuit interrupter or breaker mechanism presently to be described.

The interrupter cam 32 through its stem or spindle element 31, is driven from the shaft 26 by an interconnecting breaker timing or governor means which is operable in response to changes in engine operating speed, for effecting angular shifts of the cam 32 relative to the shaft 26, and hence relative to the engine crankshaft, to thereby advance or retard the cam-operation of the breaker or interrupter in accordance with increasing or decreasing engine speed. The governor mechanism for controlling the ignition spark advance and retard, comprises according to the presently preferred embodiment thereof, a plate-disc 34 having a hub 35 seating on the inner end 28 of the shaft 26 and suitably secured thereto. Pivotedly mounted on the disc by means of pivot pins 36, are a pair of weight-elements 37 each of substantially arcuate extent. As appears in Fig. 2, the relative pivotal arrangement of the weights is such that each tends to swing in the counter-clockwise direction under the influence of centrifugal force resulting upon rotation of the shaft 26. To the free end of each weight element is pivotally connected a link element 38, and to the free end of each of the latter elements is connected one end of a spring 40, the opposite ends of the springs 40 being suitably anchored to the disc hub 35, as shown. The cam spindle 31 is bored transversely therethrough, as at 41, and diametrically opposed slots 42 are provided in the shaft end 28, in registry with the bore 41. Projected through the slots and bore is a rod 44 having its free ends suitably pivotally connected to the link elements 38. The resulting governor mechanism as will now appear, thus effectively provides for angular shift of the cam shaft and cam relative to shaft 26, in response

to changes in engine speed, the total extent of cam shift being limited by abutment of the rod 44 with the opposite ends of the slots 42.

As appears in Figs. 1 and 3, the casing 10 is provided with spaced internal bosses 45 for the support of a frame member or plate 46 formed by preference, of insulating material, the plate being removably attached to the bosses by suitable screws 48 and its location being in the lower part of the casing, in vertical disposition as shown. The plate which serves to support the interrupter mechanism, is centrally apertured, as at 49, to receive therethrough the cam 32 and end 28 of shaft 26. The interrupter or circuit breaker device operated by cam 32, may be of any well known construction, but as here shown (Fig. 3) includes a bell crank 50 having one end 52 adapted for cam-following contact with cam 32, and its opposite end supporting a contact 53. Bell crank 50 is formed of insulating material, and is pivotally mounted intermediate its ends, on an adjustably fixed plate element or bracket 54 secured to frame plate 46 by suitable screws 56. A fixed contact 57 is carried by bracket plate 54 in position for circuit make-and-break cooperation with the movable contact 53, and its circuit connection is made to ground in any suitable manner, through the metal casing 10. The bracket also supports a conductor terminal 58, through an upstanding ear 60 from which the terminal is insulated, as by insulating washers 61. A leaf spring 62 of conducting material, has one end secured to terminal 58 and its opposite end secured to the contact 53 on bell crank 50, the spring serving to load the bell crank such as to urge the bell crank end 52 toward the cam 32, to maintain cam-following engagement thereof with the cam. The leaf spring serves also, to provide the circuit connection between the movable contact 53 of the breaker assembly, and the terminal 58. A condenser unit 63 is carried on the frame plate 46, being mounted thereon in any suitable manner as at 64. The condenser as will be understood, is provided for connection across the interrupter contacts 53—57 to dampen arcing upon separation of the contacts in the interrupter operation.

According to the present disclosure, the frame plate 46 serves as an operative support for the distributor drive connection from shaft 26. To this end the plate is formed to provide a horizontal, laterally projecting bearing member 65, arranged on the upper portion of the plate such

that the axis thereof is parallel to and substantially vertically above the axis of the plate aperture 49, which aperture receives therethrough the end 28 of shaft 26 and the cam 32 (Fig. 1). A stub shaft 66 is extended through the bearing member 65 and is rotatably journaled thereby by means of sleeve bearings 67. Secured to one end of the shaft 66 is a gear 68 which enmeshes a pinion 69 on the end 28 of shaft 26, the pinion in the present example, being formed integrally with the latter shaft end, as by cutting the pinion teeth in the peripheral surface of the shaft end, as indicated in Figs. 1 and 2. The stub shaft 66 is projected through an aperture 70 in an internal wall 72 of the casing 11 for driving connection with a distributor rotor (not shown) within the casing extension 14.

It will now appear that I have provided an improved and fully automatic breaker timer device adapted for effecting proper timing of contact and separation of the breaker points by the cam 32, in direct relation to engine speed.

While the invention has been described in connection with a preferred embodiment thereof, it is to be understood that various modifications may be made in the construction and assembly relation of parts, without departing from the spirit of the invention as defined by the appended claim.

I claim:

30 An automatic control device of the character described for a cam-actuated ignition circuit interrupter, the device comprising a rotatable shaft provided with an axial recess in one end and having opposite transverse slots communicating with the inner end portion of the shaft recess, a spindle rotatably received in said shaft recess and formed on its outer end to provide an interrupter actuating cam, a disc having a hub portion fixed to said shaft, opposed weight elements mounted on the disc for swinging movement responsively to centrifugal force, a pin projected through said spindle and laterally therefrom through said shaft slots, said slots each being of an extent to permit 35 movement of the pin projecting therethrough for affording a limited relative rotation of the shaft and spindle, a link element pivotally connected to the free end of each weight element and to one end of said pin, and a spring between said 40 disc hub and each link element, effective to load 45 the associated weight element.

EDWARD A. VOGEL.
